UNITED STATES PATENT OFFICE.

JOHN V. W. VANDENBURGH, OF CHICAGO, ILLINOIS.

DESIGN FOR A PAPER-WEIGHT.

SPECIFICATION forming part of Design No. 21,150, dated November 3, 1891.

Application filed October 10, 1891. Serial No. 408,365. Term of patent 3½ years.

To all whom it may concern:

Be it known that I, JOHN V. W. VANDENBURGH, a citizen of the United States, residing at Chicago, in the county of Cook and State 5 of Illinois, have invented and produced a new and original Design for Paper-Weights, of which the following is a specification, reference being had to the accompanying drawings, forming a part hereof, in which—

10 Figure 1 is a perspective view. Fig. 2 is a side elevation. Fig. 3 is a plan view.

In the drawings, A represents the top of the paper-weight oval-shaped and having its sides and the end on curved lines to present 15 from all points in elevation a raised oval-shaped face, with the sides and one end defined by curved peripheral or base lines, and having its apex or small end cut by a face in cross-plane, forming a cross-edge around the 20 apex end, with lines running therefrom over the face of the apex end, producing, when viewed in elevation, the outline of an egg having the apex end struck and crushed to be flattened and cracked.

25 B is the base on which the top A is mounted

at its apex end and rises to have a projection from the center of the base in full outline when viewed in elevation. This base B has a defining peripheral outline and has a circular panel, upon which may be placed any 30 suitable words or inscription.

The essential feature of the paper-weight is an oval-shaped body with its sides and one end on curved peripheral or base lines, presenting in relief an oval-shaped raised face, 35 which is cut at the apex or small end by an edge line around the body, with lines from the edge line over the apex end of the face, producing the effect of a defined harmonious outline, illustrating an egg having its apex 40 end struck flat and crushed, the whole seated upon a flattened base.

What I claim as new, and desire to secure by Letters Patent, is—

The design for a paper-weight, substantially 45 as herein shown and set forth.

JOHN V. W. VANDENBURGH.
